UNITED STATES PATENT OFFICE.

JOHN B. HODAPP, OF MANKATO, MINNESOTA.

CAN-FILLING MACHINE.

SPECIFICATION forming part of Letters Patent No. 356,122, dated January 18, 1887.

Application filed March 11, 1886. Serial No. 184,928. (No model.)

To all whom it may concern:

Be it known that I, JOHN B. HODAPP, of Mankato, in the county of Blue Earth and State of Minnesota, have invented a new and 5 Improved Can-Filling Machine, of which the following is a full, clear, and exact description.

The object of my invention is to provide a machine whereby cans employed for the preservation of fruits, vegetables, meats, &c., may 10 be filled automatically and evenly and the charge pressed down compactly, after which the cans are delivered to a table provided for their reception.

The invention consists of a machine of peculiar and novel construction adapted to carry 15 out the objects named, which machine will be hereinafter fully described, and specifically pointed out in the claims.

Reference is to be had to the accompanying 20 drawings, forming a part of this specification, in which similar letters of reference indicate corresponding parts in all the figures.

Figure 1 is a side view of the machine shown 25 in partial section to disclose certain details of construction. Fig. 2 is a front elevation of the machine, also shown in partial section. Fig. 3 is a vertical sectional view taken on line *y y* of Fig. 2. Fig. 4 is a sectional plan view taken on line *x x* of Fig. 1. Fig. 5 is a detail 30 view illustrating the construction of the cam employed to operate the feed-slide. Fig. 6 is a plan view of the revolving disk having a cam-faced ridge which operates a lever by which the cans are raised to bear against the 35 under side of the fillers. Fig. 7 is a plan view of the feed-table; and Fig. 8 is a detail view, shown partly in section, illustrating the construction of the cam employed to intermittently advance the carrier-belt.

In building such a can-filling machine as is 40 illustrated in the drawings I provide a heavy supporting-frame, *A A*, in which there is mounted a driving-shaft, *B*, carrying fast and loose pulleys *B' B''* and a pinion, *C*, motion being imparted to the shaft by a power-transmitting belt arranged in connection with the pulleys *B' B''*. A belt-shifter, *C'*, is arranged so as to shift the belt from *B'* to *B''*, and at the time of such shifting the projecting end of the 45 belt-shifter is brought to bear against the edge of a fly-wheel, *C''*, thereby checking the momentum of the machine. The pinion *C* en-

gages with a large gear, *D*, that is fixed upon a shaft, *D'*, mounted above the shaft *B* in bearings that are held by the frame-work *A*. This 55 shaft *D'* carries a bevel-gear, *D''*, and a crank, *E*. The gear *D''* meshes with the gear *E'*, having double the number of teeth, said gear *E'* being carried by a vertical shaft, *E''*, which carries a bevel-pinion, *a*, that engages with a 60 gear, *a'*, mounted on a shaft, *F*, arranged in the cylindrical chamber *F''* at the bottom of a hopper, *F'*. Upon the shaft *F* there are arranged four radial blades or arms, *b b*, which project at right angles from the shaft and divide the cylindrical chamber *F''* into four compartments, each of which compartments is in turn centrally divided by a partition, *c*. 65

Just below the hopper *F'* there is arranged a feed-table, *G*, which is circular and so 70 mounted that the shaft *E''* passes through its axis, and this shaft *E''* carries arms *G' G'*, that are arranged just above the feed-table *G*, each of which arms is provided upon one side with double semicircular faces *c' c'*, so that as the 75 arms are revolved through the medium of the shaft *E''* they will scrape up the two piles of matter that have been deposited upon the feed-table by the revolution of the shaft *F* and its attachments, and will carry such matter 80 forward, so that it will be dropped into the funnel-shaped fillers *H*, which project from the under side of the feed-table, as is clearly shown in the drawings, an equal amount of matter being deposited within each filler. 85

The openings at the bottoms of the fillers *H* are closed by a slide, *d*, the construction of which is probably best shown in Figs. 2 and 4. This slide is formed with an upwardly-extending plate, *d'*, which is borne upon by a 90 peculiarly-shaped cam, *H'*, which is shown in detail in Fig. 5, said cam being provided with friction-rolls *e*, arranged to bear against the face of the plate *d'*. The plate *d'* is rigidly connected to a rod, *e'*, which is supported in a 95 block, *e''*, fixed to the frame *A*. A spiral spring, *f*, one end of which is fixed to the block *e''*, is coiled about the rod *e'*, and fixed at the other end to a collar, *f'*, that is carried by the rod *e'*, the tendency of the spring being to 100 throw the slide in the direction of the arrow shown in Fig. 4, so as to bring the openings in the slide *d* in register with the openings in the bottoms of the fillers *H H*, this being

done at the time when either of the recesses f'' or f''' of the cam H' will permit the spring to act.

The relation of the gearing L' , E' , a , and a' is such that the shaft F is revolved a quarter-revolution for every full revolution of the shaft D' , while the arms $G' G'$ are carried through half a revolution for every full revolution of the said shaft D' .

10 The cans to be filled are delivered from two vertical cylinders, $J J$, within which they are piled, to an endless sectional carrier-belt, I , that is mounted upon and driven by two hexagonal drums, $I' I''$, said drums being journaled in the frame-work of the machine, as best shown in Fig. 1. Every other section of this belt I is provided with can-holding pins $h h'$, the pins h being arranged upon either side of the cans, while the pins h' are arranged 15 to come just behind the cans. Upon the other sections of the belt there are arranged supporting-stands K , having rearwardly-extending spring-arms k , the purpose of these stands K being to support the column of cans held 20 within the cylinders J when the machine is in the position shown in Fig. 3.

Upon the end of the shaft of the drum I' there is loosely mounted a lever-arm, L , which is adjustable as to length, and connected by 25 the connecting-rod L' to the crank-arm E ; and as the lever-arm L is slightly longer than the crank-arm E , it follows that at every revolution of the shaft D' a reciprocating motion will be imparted to the lever L , the idea being to bring said lever into engagement with pins l , that are mounted so as to project through the 30 end plate, l' , as shown in Fig. 8, three of said pins being employed, they being located at every other angle of the drum and held extended by springs l'' , but being so arranged that when the lever L is on its downward stroke they will be pressed inward, the lever at this time sliding over their bevel-faces m .

From this construction it follows that at 40 every revolution of the shaft D'' the drum I' will be carried forward one-third of a revolution, which movement of the belt will carry the cans from their position in the bottom of the cylinders J to a position just beneath the 45 fillers, the cans sliding down the spring-arm k into engagement with the pins $h h'$ of the following section, being at this time guided and held by rods $n n$, which extend across the upper face of the belt and are secured to the 50 cylinders J and to a receiving-table M , two of these rods n being used in connection with each of the cylinders J .

In order that the cans may be supported above the rods n , I provide the sections which 55 carry the pins $h h'$ with strips o , upon which the cans rest, the rods n being arranged beneath the upper face of said strips. As the cans are advanced beneath the fillers H , they are raised so as to be brought against the bottom of a plate, N , that is carried by the fillers, and above which the slide d is operated, suitable apertures being formed in the plate N to

permit of the passage of the filling material.

This raising of the cans, as stated in the last paragraph, is accomplished by means of a 7c rack, O , that is pivotally mounted between the drums $I' I''$, being supported on brackets p , that are held by the frame A . This rack O carries friction-rolls $o' o'$, and is pivotally connected to a lever, P , which is in turn pivotally connected to the frame-work of the machine, as best shown in Figs. 2 and 4. The lever P carries a roller, q' , which rides upon the face of a cam-faced ridge, q , formed upon a revolving disk, R , that is mounted at the lower end 80 of the shaft E'' , the cam q being so formed and the parts so timed that, just as the cans pass under the plate N , they will act to raise the lever P , and consequently throw the cans up against the under side of the plate N . Just at 85 the time that the cans are thrown against the under side of the plate N , two plungers, $S S$, that are carried by the square shaft S' , are forced downward into the fillers, so that the material contained by the fillers is forced downward and outward into the cans, motion being 90 imparted to the shaft S by means of a connecting-rod, T , which engages with the crank-arm E , the idea of squaring the shaft S' being to prevent its turning, so that the plungers 95 which it carries will always register with the fillers.

After the cans have been filled the next movement of the belt I will carry the cans just above the drum I' , and a still further movement of the belt will carry the cans forward, so that they will ride along over the rods n , being at this time guided by the horizontal arms p' , the forward movement of the cans being brought about by the pressure exerted 105 by the pins or arms h' .

The pins l engage with a stop-plate, m' , at the completion of the forward throw of the lever L , and prevent any backward movement of the belt I .

A roller, m'' , is arranged forward of the tubes J , to insure the proper seating of the cans on the belt.

Having thus fully described my invention, what I claim as new, and desire to secure by 115 Letters Patent, is—

1. In a can-filling machine, the combination, with a hopper, of a feed-table and arms G' , formed with double semicircular faces, substantially as described.

2. In a can-filling machine, the combination, with a hopper and its shaft carrying radial blades and central partition, e , of a feed-table, G , and arms G' , having double semicircular faces, substantially as described.

3. In a can-filling machine, the combination, with a hopper, of a shaft, F , carrying radial blades $b b$, and a central partition, e , a feed-table, G , arms $G' G'$, fillers $H H$, slide d , cam H' , rod e' , spring f , and an operating-shaft, E'' , substantially as described.

4. In a can-filling machine, the combination, with a driving-shaft, of a vertical shaft-carrying gear, E' and a , and a cam, H' , a hopper,

F', shaft F, carrying radial blades b b, and a central partition, c, a feed-table, G, arms G' G', fixed to the vertical shaft, fillers H H, and a slide, d, operated by the cam H', the spring f, 5 and rod e, secured to the slide, substantially as specified.

5. In a can-filling machine, the combination, with a hopper and its delivery mechanism, of a feed-table, revolving arms G', fillers H, plungers S, and slide d and means for operating it, an endless carrier-belt, and an operating mechanism, substantially as described.

6. In a can-filling machine, the combination, with a delivery mechanism, consisting of a hopper, feed-table, revolving arms, fillers, plungers, and slide, of an endless carrier-belt and its operating mechanism, and a mechanism, substantially as described, whereby the cans carried by the belt are raised against plates 20 carried by the fillers, all substantially as described.

7. In a can-filling machine, the combination, with a charge-delivery mechanism, of an endless carrier-belt mounted on drums I' I", and 25 operated by a lever, L, that is connected to a crank-shaft by a connecting-rod, L', the drum I" being provided with yielding pins l, a piv-

totally-mounted rack, O, lever P, and cam R, substantially as described.

8. In a can-filling machine, the combination, 30 with a hopper and its delivery mechanism, a feed-table, revolving arms, fillers, and slide, of an endless carrier-belt carrying guiding-pins h h', and supporting-racks K, can-carrying cylinders J, rack O, rods n, and an operating 35 mechanism, substantially as described.

9. In a can-filling machine, the combination, 40 with a driving-shaft carrying a pinion, of a shaft, D', gear D, and bevel-gear D'', shaft E'', bevel-gears E' and a, hopper F', shaft F, driven by gear a', and carrying blades b b, and a central partition, c, arms G', carried by the shaft E'' and formed with double semicircular faces, fillers H, plungers S, operated through connection with the crank E, formed on the shaft 45 D', slide d, cam H', endless carrier-belt I, mounted on drums I' I", the drum I" being provided with pins l, lever L, connected to the crank E by a rod, L', rack O, lever P, and cam R, all substantially as described.

JOHN B. HODAPP.
